UNITED STATES PATENT OFFICE.

FRANK X. MANTSION, OF PHILADELPHIA, PENNSYLVANIA.

AUTOMATIC SWITCH.

No. 873,572.

Specification of Letters Patent.

Patented Dec. 10, 1907.

Application filed October 26, 1906. Serial No. 340,753.

To all whom it may concern:

Be it known that I, FRANK X. MANTSION, a citizen of the United States, residing at Philadelphia, county of Philadelphia, and 5 State of Pennsylvania, have invented a certain new and useful Improvement in Automatic Switches, of which the following is a specification.

My invention relates to a new and useful 10 improvement in automatic switches, and is especially adapted for use in trolley lines, and has for its object to provide a suitable mechanism for automatically throwing the switch point from one side to the other when the car 15 is moving in either direction.

With these ends in view, this invention consists in the details of construction and combination of elements hereinafter set forth and then specifically designated by the 20 claims.

In order that those skilled in the art to which this invention appertains may understand how to make and use the same, I will describe its construction in detail, referring 25 by letter to the accompanying drawing forming a part of this specification, in which—

Figure 1 is a longitudinal section of the casing in which the automatic mechanism is housed, said mechanism being in perspective, and also showing the block carried by the car adapted to actuate this automatic mechanism. Fig. 2, a detail perspective of the cam slide for throwing the switch point. Fig. 3, a plan view of a switch equipped with 35 my invention. Fig. 4 is an enlarged sectional perspective.

In carrying out my invention as here embodied, *a* represents a casing which is either cast with the switch *B* or bolted, which casing is intended to house the automatic mechanism for operating the switch point *C*, the latter being of ordinary construction and pivoted so as to have a swinging movement for opening and closing the main line.

Immediately beneath the switch point and within the housing is located a slide *D*, which has formed therein a cam slot *E* and the stud *F* projecting downward from the switch point passes through this cam slot, so that 50 when the slide is moved back and forth longitudinal of the track the switch point will be thrown to one side or the other as the case may be and there locked against accidental displacement until the cam slide is again moved. This cam slide has attached thereto a rod *G* which connects it with the upper

end of the lever *H*, the lower end of this lever having pivoted thereto the draft rod *I*, in which is formed a hook *J* for engagement with the stud *K*, upon the actuating lever *L*, 60 so that when this draft rod is drawn forward by the actuating lever as will be hereinafter set forth, the cam slide will be drawn in the direction of the arrow adjacent thereto, and this will throw the switch point *C* so as to 65 open the main line and close the branch line.

In order that the cam slide may be moved in the opposite direction for closing the main line and opening the branch line, I pivot a lever *M* in such manner that its upper end 70 bears against the forward end of the slide, the lower end of this lever being connected by the rod *N* to the lever *O*. The upper end of the lever *O* has pivoted thereto the draft rod *Q*, having a hook *R* formed thereon similar 75 to the hook *J* and adapted to engage with the stud *K*, so that when this draft rod is drawn forward by the actuating lever *L* the cam slide will be forced rearward by the upper end of the lever *M*, as will be readily 80 understood. As the pulling of the draft rods in the same direction by the actuating lever *L* moves the cam slide first in one direction and then the other, it is essential that only one of the draft rods be in engagement 85 with the stud *K* of the actuating lever at a time, and to accomplish this result the draft rod *Q* has an extension *Q'*, the end of which extension carries a pin *Q''* adapted to ride upon the spring bar *Q''*, and when the 90 hook *R* is in engagement with the stud *K* and the actuating lever forced forward carrying with it the draft rod *Q* and its extension, the pin *Q''* will pass under the inclined bar *Q''*, the bar *Q''* springing downward 95 sufficiently to permit this pin to pass beyond the bar *Q''*. When the actuating lever is released it will be returned to its normal position by the weight *S* upon the outer end of the extension *S'* of the actuating lever, and 100 this reverse movement of the actuating lever will force the draft rod *Q* upward by the action of the stud *K* upon the inclined portion of the hook *R*. The draft rod *I* is also provided with an extension *I'*, carrying 105 a pin *I''*, adapted to ride upon the spring bar *I''*, and this pin when the draft rod is drawn upon will ride beneath and beyond the inclined bar *I''* and be forced upward by the inclined portion of the hook *J* when the 110 stud *K* is moved backward by the actuating lever *L*.

When the draft rod Q is drawn forward by the actuating lever, as just described, the draft rod I will be drawn backward by the rearward movement of the cam slide D, drawing upon the lever H through the rod G, and this backward movement of the draft rod I will draw the pin I² over the upper edge of the inclined bar I⁴, and to prevent the pin from dropping down at this time I provide a dog T carried by the upper end of the lever T', the lower end of which lever is connected by the rod T² with the sliding block T³. This dog lies beneath the path of the pin I² when the latter is drawn over the top of the bar I⁴, and is normally held in this position by the weight T⁴ carried by the lever T⁵, which is connected with the lever T' by the lever T⁶. Thus the draft rod I will be held up out of engagement with the stud K so long as the dog T remains in its normal position, but when the pin Q² in its forward movement with the draft rod Q passes under the inclined bar Q⁴ it will come in contact with the block T³ and force this block backward, and in so doing will so actuate the lever T' as to withdraw the dog T from beneath the pin I² permitting the draft rod I to drop downward putting the hook J in position to engage the stud K upon the next forward movement of the actuating lever L. When the draft rod I is drawn forward by the next movement of the actuating lever, the pin Q² will be drawn over the top of the bar Q⁴ and on to the dog U carried by the lever U', this lever being held in its normal position by the weight U⁴ through the lever U⁵ connected by the rod U⁶ with said lever U', thus duplicating the operations just described in connection with the draft rod I, and when the pin I² forces the block U³ backward the rod U² will actuate the lever U', thereby withdrawing the dog U from beneath the pin Q², permitting the draft rod Q to again drop into the position where its hook R may again engage the stud K. The upper end of the actuating lever projects through a slot in the rail, and a secondary actuating lever L' is pivoted within the casing at the other end of the switch, and also projects through a slot in the rail in order that the switch point may be thrown by a car coming in either direction, and these two actuating levers are connected together by the rods L² and L³, an intermediate lever L⁴ serving to properly transmit the draft upon these rods. For operating these actuating levers I locate upon each car an inclined block V fitted to slide upon a corresponding inclined bracket W, and this block is connected to the bell crank lever X by the rod Y, the horizontal member of the bell crank lever having an upright post Z pivoted thereto which the motorman may depress when he desires to operate the switch, the depressing of which will draw forward the

block V causing it also to move downward until the toe of the dog a rests upon the lower surface of the rail, and as this dog is pivoted and held in its normal position by the spring b when the toe thereof comes in contact with the rail, it will be drawn backward dragging along the rail until it reaches the slot in which the actuating lever is located, when it will spring forward and operate this lever to bring about the movements of the mechanism before described for throwing the switch point.

In order that the rails may be kept clear of dirt or slush at the points where the actuating levers are located, I provide a brush d upon the under side of the block V, and when this block is drawn downward this brush will also come in contact with the surface of the rail and sweep the same clean.

It is to be noted that when the switch has been thrown to one side or the other it will be locked against displacement by the cam slide, and cannot be moved until one or the other of the actuating levers is operated, thus avoiding the accidental displacement of the switch point which often causes annoyance and loss of time.

Having thus fully described my invention, what I claim as new and useful, is—

1. In an automatic railway switch, the combination of a pivoted switch point, a cam slide adapted to move said point in either direction, a lever H, a rod connecting said lever with the cam slide, a lever M adapted to actuate the cam slide in one direction, a lever O, a rod connecting the last named lever with the lever M, an actuating lever and means for alternately operating the levers H and O from the actuating lever, as and for the purpose set forth.

2. In an automatic switch, a pivoted switch point, a cam slide for throwing the switch point to one side or the other, a lever H, a rod connecting said lever with the cam slide so as to pull the latter in one direction, a lever M adapted to force the cam slide in the opposite direction, a lever O, a rod N connecting the last named lever with the lever M, two draft rods, one attached to each of the levers H and O, an actuating lever adapted to operate the draft rods, and means for bringing first one and then the other of the draft rods in position to be operated by the actuating lever, as specified.

3. In an automatic switch, a pivoted switch point, a cam slide for throwing the switch point to one side or the other, a lever H, a rod connecting said lever with the cam slide so as to pull the latter in one direction, a lever M adapted to force the cam slide in the opposite direction, a lever O, a rod N connecting the last named lever with the lever M, two draft rods, one attached to each of the levers H and O, an actuating lever adapted to operate the draft rods, means for bringing

ing first one and then the other of the draft rods in position to be operated by the actuating lever and a spring actuated dog carried by the car for operating the actuating lever, 5 as specified.

4. In combination with the movable switch point of a railway switch, a cam slide adapted to throw the switch point to one side or the other, two actuating levers connected together, two draft rods, a series of levers and rods connecting said draft rods with the cam slide, hooks formed upon the draft rods for engagement with one of the actuating levers and mechanism for putting 10 first one and then the other of the draft rods into connection with the last named actuating lever, as specified.

5. In combination with the actuating lever of an automatic switch of the character described, two draft rods each having 20 a hook formed therein for engagement with

the stud upon said actuating lever, an extension formed upon each of the draft rods, a pin carried at the outer end of each extension, spring bars upon which each of the pins 25 is adapted to travel, two inclined bars under which the pins are adapted to pass, a swinging dog arranged adjacent to each of the inclined bars, a sliding block located back of each of said inclined bars and means connected with the blocks for actuating the opposite dog whereby dogs will be swung out of their normal positions, as and for the purpose set forth.

In testimony whereof, I have hereunto 30 affixed my signature in the presence of two subscribing witnesses.

FRANK X. MANTSION.
